UNITED STATES PATENT OFFICE

HARRY LE-VAN HORNING, OF WAUKESHA, WISCONSIN

INTERNAL COMBUSTION ENGINE

Application filed November 13, 1916, Serial No. 130,965. Renewed April 23, 1926.

My invention relates to internal combustion engines, and its object is to provide an improved construction looking toward the elimination of "hot spots" in the cylinders, which frequently cause pre-ignition, and which make for the deterioration of the structure. The present invention relates particularly to the spark plug construction and it will be seen that I not only eliminate "hot spots" which are harmful so far as pre-ignition is concerned, but I also preserve the insulating body of porcelain, for instance, of the spark plug. In the prior art structures the spark plug comprises a main metallic body which ordinarily is threaded into the spark plug receiving ring, which, in turn, is threaded into the engine cylinder. This structure presents two difficulties. One difficulty lies in the resulting "hot spots". The threaded joints are poor conductors of heat and the smaller masses therefore become heated to an excessive degree. The other difficulty proceeds from the fact that the heat is not conducted away from the porcelain efficiently and the porcelain becomes cracked and disintegrated very quickly. The low heat conducting efficiency of the threaded joints may be illustrated by screwing a bolt into a solid body and then heating the whole to a red glow. In the process of cooling the bolt will glow long after the body is cooled.

According to my invention I mount the porcelain of the spark plug directly in a properly formed opening in the cylinder head, the cylinder head being cooled by a water jacket in the usual manner. I also provide means for securing the porcelain in the cylinder head in such a way as to secure heat conduction of great efficiency and accordingly hot spots are avoided and the porcelain is prevented from being heated to a harmful degree.

I shall now describe my invention in detail by reference to the accompanying drawings in which—

Figure 1 is a cross-sectional view of an internal combustion engine embodying the features of my invention;

Figure 2 is an enlarged view of the spark plug structure;

Figure 3 shows a modification; Figure 4 shows another modification; and Figure 5 shows still another modification. Referring first to Figure 1 it will be seen that the engine is provided with the crank case 6 in which the crank shaft 7 is mounted. Although there may be a plurality of cylinders, only one cylinder 8 is shown, by reason of the nature of the view, this cylinder having the piston 9 connected with the crank shaft 7 by means of the connecting rod 10. The cylinder is surrounded on the top and sides by means of the water jacket 11 which is fed thru a pipe 12 from a pump 13, the pipe 14 leading from the pump 13 to complete the ordinary circulating system. The particular view happens to show the exhaust valve 15 which is operated from the cam-shaft 16, this valve controlling the exhaust port 17 leading to the exhaust manifold 18 in the usual manner.

The spark plug is provided in the cylinder head and the arrangement is shown in detail in Figure 2. It will be seen that the cylinder head is provided with a spark plug opening 19 which has a shoulder 20. A gasket 21 of some such material as copper asbestos is laid upon the shoulder 20 and the porcelain 22, having the flange 23, is laid upon this gasket, as shown. On top of the flange 23, there is provided another gasket of some such material as copper asbestos, indicated at 24, and a clamping ring 25 threaded directly in the cylinder head, as shown, is screwed down on top of the gasket 24, as shown, with a main cooling space between the ring 25 and the porcelain. The electrode 26 is mounted in the porcelain 22 in the usual manner, being provided with the connecting terminal 27 at the upper end thereof. The electrode 26 is placed in proper juxtaposition to the cylinder formations 28 which constitute the other terminal of the spark gap, the circular face of flange 23 acting as a guide and formations 28 being grounded in the usual way in order to form part of the ignition circuit. In this way the porcelain 22 is disposed directly in the cylinder head without the employment of any intervening parts. The porcelain is so disposed in the cylinder head

that the heat therein may readily pass to the larger mass without the interference of obstructions such as poor joints. It will be clear that it is not necessary that the porcelain 22 be held in position in the precise manner shown, it being entirely practical to use a flange ring bolted down on top of the cylinder and extending down on top of the gasket 24, instead of the threaded gland nut 10 shown.

The structure illustrated in Fig. 3 is like that illustrated in Fig. 2 except that the spark plug itself is provided with two electrodes 29 and 29', the cylinder formations 28 15 of Fig. 2 being then entirely omitted. In this case there are two connecting terminals 30 and 30' on the spark plug itself.

The structure illustrated in Fig. 4 is like that of Fig. 2 except that the gland nut 31, 20 which is employed instead of the gland nut 25, is cut back, as illustrated at 32 in order to make room for a stuffing of some compressible material 33 of high heat conducting quality, such as tin, the idea being to 25 provide a large heat conducting contact area for the porcelain and also, for such area, an intimate contact.

The structure illustrated in Fig. 5 is like that of Fig. 4 except that the gasket 24 is 30 omitted and the stuffing 34 is so formed as to fill the entire space under the gland nut 31. It will be seen that this stuffing secures the proper seal and at the same time provides a considerable contact area for conducting 35 heat away from the porcelain, and with a very intimate contact. The parts being disposed directly in the cylinder head, the conduction of the heat is direct and effective and the advantages hereinbefore set 40 forth are obtained simultaneously with an advantageous simplification of structure.

I claim:

1. In an internal combustion engine, a cylinder, an opening in the head of said cylinder, an insulating body set directly in said opening, a clamping ring threaded directly in said cylinder head and retaining said body in said opening, a filling of tin between said body, said ring and said cylinder head, and a spark gap electrode mounted in said body.

2. In an internal combustion engine, a cylinder, an opening in the head of said cylinder, an insulating body set directly in said opening, means for clamping said body in said opening, a filling of tin between said body, said ring and said cylinder head, and a spark gap electrode mounted in said body.

3. In an internal combustion engine, a cylinder having an opening in the head thereof, a water jacket in said head surrounding and in close proximity to said opening, said opening having an outwardly facing shoulder therein and being reduced at its inner 65 end, an insulating member comprising an

elongated central body with a reduced annular flange, said member being disposed in said opening over said shoulder with the axis of said body and flange coincident with that of said opening and with relatively soft material of high heat conductivity directly intervening, means for clamping said member in said opening, and an electrode mounted axially in said central body and extending downwardly to said reduced portion of said opening to form a spark gap with an integral portion of said head.

In witness whereof, I hereunto subscribe my name this 9th day of November A. D. 1916.

HARRY LE-VAN HORNING.
